WIG BLOCK SUPPORT OR THE LIKE

George J. D'Zamko, 529 11th Ave. N.,
Jacksonville Beach, Fla. 32250

Filed Apr. 27, 1970, Ser. No. 22,645

Term of patent 14 years

Int. Cl. D28—03

U.S. Cl. D86—10

FIG. 2

FIG. 1

FIG. 3

FIG. 4

FIG. 5

FIG. 1 is a side elevational view of the wig block support showing my new design;

FIG. 2 is a rear elevational view thereof;

FIG. 3 is a front elevational view thereof;

FIG. 4 is an enlarged top plan view thereof; and

FIG. 5 is an enlarged cross-sectional view taken on line 5—5 of FIG. 1.

The fragmentary broken line representation of a table edge in FIGS. 1 and 2 is for purposes of illustration only.
I claim:

The ornamental design for a wig block support or the like, substantially as shown and described.
